UNITED STATES PATENT OFFICE.

JOSEPH ROTCHCHILD, OF BAYONNE, NEW JERSEY, ASSIGNOR TO THE JOHN SIMMONS COMPANY, OF NEW YORK, N. Y., A CORPORATION OF NEW YORK.

AWNING.

No. 918,598.

Specification of Letters Patent.

Patented April 20, 1909.

Application filed October 5, 1907. Serial No. 395,994.

To all whom it may concern:

Be it known that I, JOSEPH ROTCHCHILD, a citizen of the United States, residing at Bayonne, in the county of Hudson and State of New Jersey, have invented certain new and useful Improvements in Awnings, of which the following is a specification.

This invention relates to awnings, and its novelty consists in the construction and adaptation of the parts as will be more fully hereinafter pointed out.

The object of the invention is to provide an awning which can be made vertically narrow and have a wide horizontal extension or vertically wide and have a narrow horizontal extension, one which can be partly folded against the structure to which it is secured, provided with a weather-tight housing for the roll when not in use, one in which the roll is always under spring tension and may be quickly wound and unwound and yet may be securely locked at any desired point and the spring of the winding roll of which may have its tension increased or diminished at will.

In the drawings, Figure 1 is a front elevation of an awning embodying my invention showing the roll within its housing and the frame folded against the building; Fig. 2 is a side elevation of the same and of the hook used in manipulating it, the extended position of the awning and frame being indicated by dotted lines; Fig. 3 is a central vertical section on the plane of the line 3—3 in Fig. 1; Fig. 4 is an enlarged central section of the winding roller and housing on the plane of the line 4—4 in Fig. 2; Fig. 5 is a view similar to that shown in Fig. 4 with the winding roll engaging the side of the casing; Fig. 6 is an end view of the roller and its shaft and pawls; Fig. 7 is a plan view of the end of the shaft and its handle; Fig. 8 is an end view of the housing and shaft latch showing the latter elevated; Fig. 9 is a miniature view of the awning frame and roll extended; Fig. 10 is a side view and partial vertical section of a modified form of the housing; Fig. 11 is a detailed view of a modified form of one of the arms of the frame and Fig. 12 is a detailed bottom plan view of one end of the roller and its retaining mechanism.

In the drawings, 10 is a window casing, or similar portion of a building, to which the awning frame is secured. This frame com-

prises, first, two upright members, 11, 11, supported at each end and one on each side of the window casing by brackets 12, 12 and screws, 12', 12', or in any other suitable manner, and so arranged that each member 11 is set a slight distance from the casing 10. It also comprises two collars 13, 13, adjustably secured by screws 14, 14, or in any other suitable manner, to the uprights 11. Two arms 15, 15, are pivoted to the upper collar 13 and two similar arms 16, 16, are pivoted to the lower collar. These pairs of arms are pivoted at their outer extremities to a link 17 from which there extends outwardly a frame rod 18 bent outwardly at 19 and again inwardly at 20, and connected to the similar link 17 at the other side of the frame. This frame rod is connected in any suitable manner to an awning roll. As herein exemplified the roll comprises an awning cloth 21 and its roller 30, and the end of the cloth remote from the roller is secured to said frame rod.

The awning cloth is secured at its inner end to a roller or drum 30 mounted on a shaft 31 journaled in the side members 32, 32, of a housing 33. These side members are here shown as formed integral with the upper brackets 12. The housing comprises a horizontally placed hood 34 open at the bottom and bent downwardly and reversed at the rear to form a gutter 35 which, if necessary, is given a slight incline to allow the water accumulated therein to run off, and which in the modified form shown in Fig. 10, may be secured to the hood by the hinge 350.

Secured to the roller 30, and to the shaft 31, is a spring 36 which is put under tension when the awning cloth is unwound from the roller and by the retraction of which spring the awning cloth is automatically rewound thereon. The end of the shaft 31 is provided with longitudinal grooves 37 adapted to engage with pawls 38 to hold the shaft against rotation.

The outer end of the shaft 39 projecting beyond one of the sides 32 is squared and is provided with a handle 40 secured to it by pivots 41, or in any suitable manner. This handle in the form illustrated consists of a strap bent inwardly and the innermost ends of which are provided with a cam surface 42. It is preferably provided with a hand grip 43. Secured to one of the side members 32 of the housing by a pivot and

placed adjacent to the handle 40 is a latch piece 44, recessed at 45 to pass over and engage with the squared end 39 of the shaft. This squared end constitutes a catch for the 5 latch 44.

The roller 30 is provided with a lateral conical flange 300 interrupted at two diametrically opposite places by notches 301 adapted to engage with an inwardly projecting tooth 302 secured to or formed integral with one of the side members 32, and preferably extending at an angle to the longitudinal axis of the roll. 10

The outer end of the awning roll is provided with one or more depending rings 210 which may be engaged by a hook 211 adapted to be used for the purpose of moving the winding roll. 15

In Fig. 11, is shown a modified form of 20 the arms 15, in which they are shown consolidated into a single bar 150 provided with forks 151, at each end. The arms 16 may be similarly formed into one forked piece.

In use the parts are assembled together 25 away from the place where they are to be erected, that is, the uprights are secured to the housing and the awning roll is fastened therein. It can then be secured in place by the mere use of the screws 12.

30 The roller 30, and its shaft 31, slots 37 and pawls 39, the shaft and roller being connected by the spring 36 are what is known in the art as the Holland roller. The awning cloth 21 is normally wound on 35 the roller 30 which is kept from unwinding by the tension of the spring 36. If now the awning roll is pulled by the use of the hook 211, or otherwise, it unwinds readily because the pawls 38 do not engage the slots 37 when 40 the motion of the roller is relatively rapid, but if the pull on the roll ceases the pawls 38, or rather the uppermost one, engages with the slot 37 and holds the roll at that point. 45

If the awning roll is pulled until the frame rod 18 is practically horizontal it will be seen that the arms 15 and 16 turn on their respective points secured to the collars 13 until they are in the position shown in 50 dotted outline in Fig. 2 and in full outline in Fig. 9, and the link 18 is horizontal. While if the awning and its frame is pushed back against the wall or frame 10, it is compactly folded and does not take up much vertical 55 space. This compactness can be further promoted by adjustably securing the frame rod 18 to the links 17; for instance by drilling holes 17^a in the latter and fastening the frame rod by a set screw 18^a.

60 If the awning is pulled down and it is desired to lock it at any point and determine its position more firmly and securely than can be done by means of the pawls 38, the handle 40 is moved to a horizontal position 65 (as shown for instance in Fig. 5) by using

the hook 21 or in any other desired manner. This motion of the handle brings the cam surface 42 against the side of the latch 44 and draws the shaft 31 over to the left (see Fig. 5) until the conical flange 300 rests 70 against the side member 32 and prevents any further rotation of the roller. Any attempt to rotate the roller after such locking action will result in the engagement of one of the notches 301 with the tooth 302 and prevent 75 its further movement.

Should the tension of the spring 36 become smaller than desired, the latch 44 can be lifted and the shaft 31 can then be rotated with respect to the roller 30 and the 80 spring 36 thus be wound up.

When the awning is rolled up in the housing as shown in Figs. 1, 2 and 3, it is completely protected from the weather by the hood 34. It is, however, desirable to drain 85 this hood to remove any moisture collecting thereon as soon as possible and the gutter 35 is provided for that purpose.

By hinging the gutter as shown in Fig. 10 90 the light is permitted to pass behind the 90 housing where such condition is deemed desirable.

It will be understood of course that modifications may be made in the detail of the device without departing from its mechanical 95 functions or mode of operation.

What I claim as new is:—

1. An awning frame having sides each composed of an arm pivoted at its upper end, a second arm pivoted at its upper end 100 and swinging downward therefrom to closed position, and a link pivoted at its ends to the free ends of said arms, said link extending downward from the lower end of the upper arm to the lower end of the second arm 105 when the frame is closed and extending outward from the second arm and in the horizontal plane thereof to the lower end of the upper arm when the frame is open, combined with an awning carrying member connecting 110 the links with each other and having ends secured to the links.

2. An awning frame having sides each composed of an arm pivoted at its upper end, a second arm pivoted at its upper end 115 and swinging downward therefrom to closed position, and a link pivoted at its ends to the free ends of said arms, said link extending downward from the lower end of the upper arm to the lower end of the second arm 120 when the frame is closed and extending outward from the second arm and in the horizontal plane thereof to the lower end of the upper arm when the frame is open, combined with an awning carrying member connecting 125 the links with each other and having ends secured to the links and moving simultaneously with the same and in the same plane as the links to both open and closed position.

3. An awning frame comprising an up- 130

right support, carrying means adjustably mounted thereon, upper and lower arms each pivotally attached to the carrying means, and a link pivoted to the confronting ends 5 of the arms and connecting the same with each other.

4. An awning frame having an upright support at each side a pair of collars adjustably mounted on each of the same, a 10 pair of arms at each side of the frame pivoted to the collars, links connecting with each other confronting ends of each pair of arms and pivoted to the same, and means connecting the sides of the frame together 15 for unitary movement.

5. An awning frame having sides each composed of an upper member comprising a pair of spaced arms pivoted to a common support, a lower member pivoted at its upper end and swinging downward therefrom to closed position, and a link pivoted at its ends to the free ends of said members and extending downward from the lower ends of the upper member to the lower end of the 25 lower member when the frame is closed and outward from the lower member and in the horizontal plane thereof to the lower end of the upper member when the frame is open, combined with an awning carrying member 30 connecting the links with each other and secured thereto and moving therewith always in the same plane as the same.

6. An awning frame having a side provided with a pair of arms, each pivotally 35 mounted at one end, a link pivoted to the confronting ends of said arms and connecting the same, and an awning carrying member adjustably secured to and extending from said link to move therewith.

40 7. An awning frame provided with an arm pivoted at one end, a link to which the other end of the arm is pivoted, a second arm pivoted to the link at one end, means to which the other end of the second arm is pivoted, and a frame rod adjustably secured to said link to project therefrom and move simultaneously therewith.

8. An awning frame each side of which 45 comprises an arm pivoted at one end, a link to which the other end of the arm is pivoted, a second arm pivoted to the link at one end and means to which the other end of the second arm is pivoted, and a frame rod having its ends adjustably secured to said links 55 to move simultaneously therewith.

9. An awning frame each side of which 50 comprises an upright, an arm, a link pivoted to one end of said arm, a second arm having one end pivoted to the link and means adjustably on the support and to which the other ends of said arms are pivoted; and a frame rod having its ends suitably secured to said links.

10. An awning frame each side of which 55 comprises an upright, an arm, a link pivoted

to one end of said arm, a second arm having one end pivoted to the link and means adjustable on the support and to which the other ends of said arms are pivoted; and a frame rod having its ends adjustably secured to said links. 70

11. In a device of the class described, two uprights, a housing for the awning roll secured between their upper ends and means for draining the housing, comprising a 75 gutter placed alongside of the housing and hinged thereto.

12. In a device of the kind described, an awning frame comprising two uprights, a transverse housing for the awning roll intermediate the uprights at their upper ends, a pair of arms pivoted to each upright, a link to which each pair of arms is secured at their outer ends, a frame rod secured to both links and an awning roll secured to the 85 frame.

13. An awning frame comprising two uprights, a bracket secured to each upright at its top, a transverse housing for the awning roll arranged between the brackets, a pair of 90 arms pivoted to each upright, a link to which each pair of arms is secured at their outer ends, a frame rod secured to both links, and an awning roll secured to the frame.

14. In a device of the kind described, an 95 awning frame comprising two uprights, a transverse housing for the awning intermediate the uprights at their upper ends, a pair of arms pivoted to each upright, a link to which each pair of arms is secured at 100 their outer ends, a frame rod secured to both links, an awning roll secured to the frame, and means for retracting the roll within the housing when the frame rod is swung upward. 105

15. An awning frame comprising two uprights, a bracket secured to each upright at its top, a transverse housing for the awning rolls arranged between the brackets, a pair of arms pivoted to each upright, a link to 110 which each pair of arms is secured at their outer ends, a frame rod secured to both links, an awning roll secured to the frame, and means for retracting the roll within the housing when the frame rod is snug 115 upward.

16. In a device of the character described, an awning frame, a roll and its shaft mounted therein, means carried by said frame and said shaft and mutually operating to prevent said shaft from rotating, and other means carried by said frame and said roll and mutually operating to prevent said roll from rotating, both of said means being relatively adjustable, substantially as described. 120

17. In a device of the character described, an awning frame, a roll and its shaft mounted therein, said roll being longitudinally adjustable with relation to said frame, 130

means carried by said frame and said shaft and mutually operating to prevent said shaft from rotating, and other means which mutually operate to lock said roll from rotation when the same is in one position in its longitudinal adjustment.

18. In a device of the character described, an awning frame, a roll and its shaft mounted to rotate, and longitudinally adjustable 10 therein, means carried by said roll and its shaft to relatively engage when the same are stationary with respect to their rotative movement, means carried by said frame and said roll which mutually operates to prevent 15 rotative movement of the latter, when the same is in one position of its longitudinal adjustment, and means for longitudinally moving said roll, forming a handle by which said shaft may be rotated irrespective 20 of said first named engaging means.

19. In a device of the kind described, an awning frame, an awning roll and a bearing for the roll, means for moving the roll longitudinally in its bearing, independent 25 of the rotation thereof, and means engaging the roll and preventing its rotation when it is in one position of its adjustment.

20. In a device of the kind described, an awning frame, an awning roll, a bearing 30 for the roll, a movable device carried by one of the parts and engaging the other and operable independent of the rotation of said roll to vary the distance between the end of the roll and the bearing, and means 35 engaging the roll and preventing its rotation in one position of such adjustment.

21. In a device of the kind described, an awning frame, an awning roll, bearings for the roll, a handle connected with the roll 40 and having a cam which engages the bearings for adjusting the roll longitudinally and means engaging the roll and preventing its rotation in one position of its adjustment.

45 22. In a device of the kind described, an

awning frame, a housing having side members, an awning roll having its bearing in the side members, means for adjusting the roll longitudinally in the housing independent of its rotation and means carried by the 50 housing and preventing rotation of the roll in one position of longitudinal adjustment thereof.

23. A housing for an awning or the like, comprising side members, a hood secured between them, a shaft journaled in bearings in the side members, a catch secured to the shaft and a latch adapted to engage therewith to prevent rotation of the shaft, a roller mounted loosely on the shaft and 55 connected thereto by a spring, and a cam pivoted on the shaft to lock the roller against one of the side members.

24. A housing for an awning or the like, comprising two side members, a hood secured between them, a shaft journaled in bearings in the side members, a catch secured to the shaft and a latch adapted to engage therewith to prevent rotation of the shaft, a roller mounted loosely on the shaft 60 and connected thereto by a spring, a handle by which the shaft can be rotated, and a cam on the handle adapted to lock the roller.

25. A housing for an awning or the like, comprising two side members, a hood secured between them, a shaft journaled in bearings in the side members, a catch secured to the shaft and a latch adapted to engage therewith to prevent rotation of the shaft, a handle by which the shaft can be 65 rotated, a roller loosely mounted on the shaft and a cam on the handle adapted to co-operate with the latch to lock the roller.

In testimony whereof I affix my signature in presence of two witnesses.

JOSEPH ROTCHILD.
